UNITED STATES PATENT OFFICE.

EUGENE THORNTON AND GEORGE M. WHEELER, OF BUTTE, MONTANA.

AIR-HEATING DEVICE FOR EXPLOSIVE-ENGINES.

1,131,016.

Specification of Letters Patent.

Patented Mar. 9, 1915.

Application filed May 20, 1913. Serial No. 768,792.

To all whom it may concern:

Be it known that we, EUGENE THORNTON and GEORGE M. WHEELER, citizens of the United States, residing at Butte, in the county of Silverbow, State of Montana, have invented certain new and useful Improvements in Air-Heating Devices for Explosive-Engines; and we do hereby declare the following to be a full, clear, and exact 10 description of the invention, such as will enable others skilled in the art to which it appertains to make and use the same.

This invention relates to air heating devices for explosive engines.

15 The object of the invention resides in the provision of a device which will efficiently heat the air before same is drawn into the carbureter whereby the efficiency of the engine is materially enhanced.

20 A further object of the invention resides in the provision of a device of the character named which will be simple in construction, and which may be manufactured and installed at a comparatively small cost.

25 With the above and other objects in view the invention consists in the details of construction and in the arrangement and combination of parts to be hereinafter more fully described and particularly pointed

30 out in the appended claim.

In describing the invention in detail reference will be had to the accompanying drawings wherein like characters of reference denote corresponding parts in the 35 several views, and in which—

Figure 1 is a view in elevation showing the improved device applied in operative relation to the carbureter and exhaust pipe of an explosive engine; Fig. 2, a longitudinal 40 section of what is shown in Fig. 1; Fig. 3, a section on the line 3—3 of Fig. 2, and Fig. 4, a detail perspective view showing the construction of the removable casing which surrounds the carbureter.

45 Referring to the drawings 10 indicates the carbureter of an explosive engine and 11 the exhaust pipe which latter includes the usual muffler 12. Surrounding the muffler 12 in spaced relation thereto is a casing 13 pro-

50 vided with a reduced extension 14 which surrounds a portion of the exhaust pipe 11 in spaced relation to the latter. The outer end of the extension 14 is provided with a lateral flange 15 upon which is secured a re-

movable casing 16 surrounding the carbureter 10. Secured to the forward end of the casing 13 beneath the exhaust pipe 11 is a forwardly opening funnel 17 and disposed in the casing 13 between same and the muffler 12 directly above the funnel 17 is a 55 partition 18.

In the use of the device it will be apparent that when the automobile with which same is associated is traveling the air will be forced through the funnel 17 into the space 60 between the casing 13 and muffler 12. The partition 18 will prevent this air from passing directly into the reduced portion 14 of the casing with the result that same will circulate around the muffler 12 and then pass 65 through the reduced portion 14 and thence into the casing 16 from where it will be drawn into the carbureter 10 in the usual and well known manner. It will be obvious with the air passing through the space 70 between the casing 13 and muffler 12 and between the space between the reduced portion 14 of the casing and the exhaust pipe 11 will be efficiently heated by the exhaust gases and will result in the supplying of a highly 75 combustible mixture by the carbureter to the engine.

What we claim is:—

The combination with the carbureter exhaust pipe, and muffler of an explosive engine, of a casing surrounding the muffler in spaced relation to the latter, a reduced extension on said casing surrounding a portion 85 of the exhaust pipes and having a laterally directed free end, a longitudinal partition 90 within the casing between the muffler and the end of the casing adjacent the extension, said partition being disposed beneath the extension, a casing surrounding the carbureter and having its interior in communication 95 with the inlet of the carbureter and the interior of the extension, and a funnel mounted on the forward end of said casing and beneath the extension, said funnel opening 100 forwardly.

In testimony whereof, we affix our signatures, in the presence of two witnesses.

EUGENE THORNTON.
GEORGE M. WHEELER.
